UNITED STATES PATENT OFFICE.

IRA E. STUMP, OF CLEVELAND, OHIO.

VALVE.

1,383,170.

Specification of Letters Patent. Patented June 28, 1921.

Application filed April 26, 1920. Serial No. 376,532.

To all whom it may concern:

Be it known that I, IRA E. STUMP, a citizen of the United States, residing at Cleveland, in the county of Cuyahoga and State 5 of Ohio, have invented certain new and useful Improvements in Valves, of which the following is a specification.

My invention relates to improvements in valves, and more particularly to that class 10 or type which are designed to be used in connection with main or supply pipes and discharge or service pipes, and in which the flow of fluid between the supply and service pipes is controlled by a main valve, and with 15 which is combined a suitable drain valve and port adapted to be operated and controlled by the main valve so that as the latter is given its initial opening and final closing movements the drain valve will be partially 20 closed and fully opened thereby. By reason of such arrangement and construction of parts, the flow of liquid or fluid therethrough is permitted to pass through the pipes when the main or supply valve is fully 25 opened, the drain ports being then fully closed by the drain valve, and when the main valve is moved to a position slightly above its fully closed position the fluid is 30 permitted to pass from both the supply and service pipes, and when moved to a fully 35 closed position, cutting off the flow of fluid from the supply pipe to the service pipe, the drain port is fully opened by the drain valve and the fluid is permitted to flow out of the discharge or service pipe in order to prevent liquid from becoming frozen within such pipe.

The primary object of the invention is to 40 provide a generally improved valve of the class indicated, which will be exceedingly simple in construction, cheap of manufacture, and efficient in use.

A further object of the invention is to 45 provide a valve in which the main valve and valve chambers are so arranged and disposed relative to the adjacent parts, and particularly with respect to the bonnet or cap carrying the valve stem, that the fluid or liquid will be effectively prevented from 50 getting into the joints or openings of the bonnet or cap above the main valve and escaping therefrom.

With the above mentioned and other ends 55 in view, the invention consists in the novel construction, arrangement, and combination of parts, hereinafter described, illustrated in

one of its embodiments in the accompanying drawings, and particularly pointed out in the appended claims.

Referring to the drawings, forming a part 60 of this specification, Figure 1 is a side elevation of a valve constructed in accordance with this invention, the main or supply valve being in its open position, and the drain valve being in its closed position.

Fig. 2, a vertical central longitudinal sectional view taken on line 2-2 of Fig. 3.

Fig. 3, a transverse sectional view taken on line 3-3 of Fig. 1.

Fig. 4 a longitudinal horizontal sectional 70 view taken on line 4-4 of Fig. 1.

Similar numerals of reference designate like parts throughout all the figures of the drawings.

The valve body 1, may be of any suitable 75 and convenient form, and is provided at one side with a supply branch 1^a, adapted to be connected to a suitable main or supply pipe, and a discharge or service branch 1^b, adapted to be connected to a suitable discharge 80 or service pipe, said supply and service branches being separated by means of an intermediate wall or partition 1^c, adapted to divert the fluid or liquid beneath the main valve hereinafter described and to form a 85 seat for the same when fully closed.

The wall or partition, 1^c, is provided with a drain valve chamber 1^d for the reception of the drain valve hereinafter described, and is provided with a drain port 1^e, adapted to 90 communicate with the service branch 1^b when opened, and with a second drain port 1^f, extending to one side of the valve body for the discharge of fluid therefrom.

The valve body is provided at its top with 95 a cylindrical extension 1^g, threaded on its exterior, said extension or head 1^g being provided on its interior with a main valve chamber 1^h, and it will be observed that the main valve chamber 1^h is arranged immediately 100 above the drain valve chamber 1^d and concentric with the latter.

The bonnet or cap 2, is threaded on its interior to thread upon the extension or head 1^g, and may be drawn up by means of the angular head 2^a, said cap or bonnet being adapted to carry the threaded spindle or valve stem 3, provided with the usual wheel 4, and carrying at its lower end the main and drain valves 5 and 6, respectively, operating in the main and drain chambers 1^h and 1^d, respectively.

It will be seen that, in the present instance, the main and drain valves 5 and 6, on the spindle 3, are in the specific form of piston valves and, in the present instance, are made up of suitable layers of packing material secured in position by means of the attaching and clamping nuts 5^a and 6^a, respectively.

It will be seen that the wall or partition, 10 1^c, provided with the drain chamber 1^d and drain ports 1^e and 1^f, is adapted to form a seat for the main valve 5 when the latter is closed, and that when the main valve is closed the flow of fluid is cut off from the 15 supply branch to the service branch, and the respective pipes connected therewith, and at the same time the relative arrangement of the ports 1^e and 1^f and the valves 5 and 6 is such that fluid or liquid from the service 20 branch 1^b will be permitted to pass through the drain port 1^e into the drain chamber, and between the valves 5 and 6, passing outwardly through the drain or ejection port 1^f at one side of the valve body.

Should it be desired to drain both the supply and service pipes through the respective supply and service branches of the valve, the main and drain valves 5 and 6 will be moved downwardly slightly below the position indicated in Figs. 2 and 3 of the drawings, so as to only partially uncover the ports 1^e and 1^f, and also with the main valve slightly above its seated position thereby permitting the fluid to pass from the supply 30 branch 1^a over the top of the wall 1^c and into the drain chamber 1^d, and also over the same and through the drain port 1^f thereby draining both pipes.

From the foregoing description, taken in 40 connection with the accompanying drawings, the operation and advantages of my invention will be readily understood.

Having thus described one of the embodiments of my invention, without having attempted to set forth all the forms in which it may be made or all the modes of its use, what I claim and desire to secure by Letters Patent, is,—

1. A valve, comprising a valve body provided with a main valve chamber and a subjacent alining drain chamber, a valve stem carrying concentric main and drain valves operable therein, and drain ports communicating with said drain valve chamber and the interior and exterior, respectively, of said valve body and adapted to be partially opened and fully closed by said drain valve with the initial closing and fully opening movements of said main valve.

2. A valve, comprising a valve body provided at its top and median portions with main and drain valve chambers, respectively, a valve stem carrying main and drain valves therein, said median portion having drain 60 ports communicating with said drain valve

chamber and the interior and exterior portions of said valve body and adapted to be initially opened and fully closed by said drain valve with the initial closing and full opening movements of said main valve.

3. A valve, comprising a valve body provided with a main valve chamber and a subjacent drain valve chamber and drain ports, a main valve seat formed on the wall of the drain valve chamber, said main valve chamber communicating with the drain valve chamber when the main valve is opened and a valve stem carrying a main valve and a subjacent concentric drain valve adapted to fully open and close said drain ports with the final closing and full opening movements of said main valve whereby said drain ports drain the supply and service pipes when the main valve is partially closed and drain the service pipe only when the main valve is fully closed.

4. A valve, comprising a valve body having supply and service branches and main and drain valve chambers, the drain chamber being provided with drain ports and one of said ports forming an inlet port communicating with the service branch of said valve body and the other communicating with the exterior portion of said valve body, a valve stem carrying concentrically arranged piston valves operable in said main and drain valve chambers, said supply piston valve operating to open and close said drain valve chamber and said drain valve piston being so arranged relative to said supply piston valve as to be initially opened and partially closed with the initial closing and initial opening movements of said supply piston valve.

5. A valve, comprising a valve body having superposed main and drain valve chambers, said valve body having supply and service branches and provided with drain ports communicating with said drain chamber, one of said ports communicating with the service branch of said valve body and the other communicating with the exterior portion thereof, a valve stem carrying piston valves operable in said supply and drain valve chambers, said drain valve piston being so arranged relative to said main piston valve and drain ports as to be fully opened and partially closed with the final closing and initial opening movements of said main piston valve, respectively.

6. A valve, comprising a valve body provided with a main valve chamber and having a subjacent partition having a drain valve chamber and drain ports, said partition being arranged to form a seat for the main valve in said main valve chamber and said main valve chamber communicating with the drain valve chamber when the main valve is opened, and a valve stem carrying concentrically arranged main and drain valves op-

- erating in said main and drain valve chambers, respectively, and adapted to fully open and partially close said drain ports with the final closing and initial opening movements 55 of said main valve whereby said drain ports are fully closed when the main valve is fully opened and are adapted to drain the supply and service pipes when the main valve is partially closed and to drain the service 10 pipe only when the main valve is fully closed.
7. A valve, comprising a valve body provided with supply and service branches separated by a median wall having a cylindrical drain valve chamber, said valve body being 15 provided with a top extension having a cylindrical main valve chamber above said drain valve chamber and said median wall, and the drain valve chamber being provided with inlet and eduction ports communicating 20 respectively with said service branch and the exterior of said valve body, a bonnet removably mounted on said top extension above said main valve chamber, and a valve stem threaded in said bonnet and provided 25 with main and drain piston valves movable in said chambers, said main piston valve being adapted to be seated on said wall, and to open and close communication between the supply and service branches, and said 30 drain piston valve being arranged to partially close and completely open said inlet and eduction ports with the initial opening and full closing movements of said main valve.
- 35 8. A valve, comprising a valve body provided with supply and service branches separated by a central partition having a cylindrical drain valve chamber, said valve body being provided with a threaded cylindrical top having a main valve chamber above said drain valve chamber and said partition, said partition being provided with inlet and eduction ports communicating 40 respectively with said service branch and the exterior of said valve body, a bonnet threaded on said cylindrical top above said supply valve chamber, and a valve stem carried by said bonnet and provided with main and drain piston valves movable in said chamber, 45 said main piston valves being adapted to be seated on said partition and close communication between the main and drain valve chambers with the final closing movement 50 thereof, and said drain piston valve arranged to completely open and to partially close 55 said drain openings with the full closing and initial opening movements of said main valve, respectively.
9. A combined service and drain valve, comprising a valve body provided with supply and service branches separated by a partition having a drain valve chamber intersected by drain ports communicating with the service branch and exterior of the valve body respectively, a main valve chamber arranged above said drain valve chamber and said partition, and a valve stem provided with main and drain valves operating in 60 said main and drain valve chambers, respectively, said main valves being adapted to be seated on said partition and close communication between said supply and service branches, and said drain valve being arranged to open said drain ports to permit 65 fluid to pass from said service branch to the exterior of the valve body when the main valve is fully closed, and to permit fluid to flow therethrough from both branch pipes when the main valve is between its fully 70 closed and fully opened positions. 80
10. A combined service and drain valve, comprising a valve body provided with supply and service branches separated by a partition wall having a drain valve chamber intersected by drain inlet and eduction ports 85 communicating with the service branch and exterior of the valve body respectively, a main valve chamber arranged above and adapted to communicate with said drain valve chamber of said partition when the 90 main valve is opened, and a valve stem provided with main and drain valves operating in said main and drain valve chambers, respectively, said main valve being adapted to be seated on said partition wall and to close 95 communication between said supply and service branches and said drain valve being arranged to open said drain ports to permit fluid to pass from said service branch to the exterior of the valve body when the main 100 valve is fully closed and to permit fluid to flow therethrough and through said drain chamber from both supply and service branches when the main valve is between its fully closed and fully opened positions. 105

In testimony whereof I have affixed my signature.

IRA E. STUMP.
